UNITED STATES PATENT OFFICE

WILLIAM H. BRESNAHAN, OF LYNN, MASSACHUSETTS, ASSIGNOR TO COMPO SHOE MACHINERY CORPORATION, OF NEW YORK, N. Y., A CORPORATION OF DELAWARE

METHOD OF AFFIXING SOLES

Application filed April 17, 1929. Serial No. 355,700.

This invention relates to methods of manufacturing footwear, and, more particularly, to methods of affixing outer soles to lasted uppers by means of adhesive cement.

5 A general object of this invention is to provide an efficient, rapid and economical method of affixing the outer soles to lasted uppers as aforesaid.

10 A more specific object of the invention is to provide a method of affixing outer soles to lasted uppers by means of adhesive cement, said method including a series of correlated steps insuring a rapid and accurate alignment and laying of the sole and a firm union 15 between the outer sole and the lasted upper, whereby the efficiency and rapidity of production of shoes of high quality will be improved.

Other objects of the invention will in part be obvious and will in part appear herein- 20 after.

The invention accordingly comprises the several steps and the relation and order of one or more of such steps with respect to each of the others thereof which will be exemplified in the method hereinafter disclosed, and 25 the scope of the application of which will be indicated in the claims.

For a fuller understanding of the nature and objects of the invention reference should 30 be had to the following detailed description taken in connection with the accompanying drawings, in which:

Figure 1 is a bottom plan view of an outer sole and lasted upper, showing the sole 35 aligned and generally positioned upon the upper;

Fig. 2 is a side elevation of Fig. 1, showing a further step in the method;

40 Figs. 3 and 4 are bottom plan and side elevational views, showing the step of preliminary laying of the sole; and

Figs. 5 to 7 are plan and side elevational views illustrative of the subsequent sole-laying and -affixing operations.

45 The principles of the present invention are applicable generally to footwear. For simplicity of illustration and description, the drawings and specification of the present application will be confined to an exemplification of the manufacture of women's shoes of

the Louis wood-heel type. It is therefore to be understood that the word "shoes" as used herein is intended, whenever the context permits, to include other types of footwear, such, for example, as women's Cuban wood heel, 55 men's and children's shoes, boots, lounging slippers and the like.

The lasted upper and the outer sole to be affixed thereto may be produced in any desired manner to render them affixable to one another, although it is preferable that the lasted upper shall be made without the use of staples, stitches or tacks in the shank and fore part, as is exemplified in my co-pending application Serial No. 351,177, filed March 30, 1929, and that the outer sole shall be prepared in a manner similar to that disclosed in my co-pending application which issued September 22, 1931, as Letters Patent No. 1,824,654, in which the extreme margin of the 65 forepart is free from cement in order that it may not adhere throughout to the upper, and will allow of the trimming, burnishing, setting and wood-heel-affixing operations 70 usually carried out. 75

Referring more particularly to the illustrations in Figs. 1 and 2, the outer sole 10, split for the wood heel as at 11, is preferably first attached to the lasted upper 12 by means of one or more locating elements 13 placed 80 at the heel. These elements may be tacks or equivalent means, such as pegs, staples or the like, and in certain cases, may be omitted if desired. The use, however, of some locating 85 means facilitates the subsequent operations. 85

Adjacent sides of the margins of the fore parts of the lasted upper and of the outer sole, and preferably the entire shank of each, are then rendered adhesive and the outer sole is temporarily laid by hand, as indicated at 90 14 in Figs. 3 and 4. The desired adhesive-ness may be obtained in any suitable manner, and may be formed on either one or both or between the lasted upper and the outer sole, although it is preferable that both the 95 lasted upper and the outer sole shall have been previously cemented, the cement being allowed to dry, and that just prior to the aforesaid temporary locating operation the cemented surfaces of each shall be treated 100

with a cement solvent or softener, as is indicated by the brush 15.

While the adhesive is still in a tacky condition, the shoe is then placed in a pressure jack 5 such as that indicated by the numerals 16 in Figs. 5 to 7, and is clamped against an inflatable pad 17, whereupon the pad is inflated slightly, as, for example, to a pressure of about 5 to 10 pounds per square inch and 10 as is indicated particularly in Figs. 5 to 7, the upper is given its final adjustment with respect to the outer sole, whereupon the final sole-affixing pressure of upwards of 40 lbs. is imparted to the pad, which pressure is maintained until the cement has set.

Although any suitable pressure mechanism may be used in carrying out the steps of the method last referred to, it is preferred that a pressure jack of the type similar to 20 that described in my co-pending application Serial No. 272,449, filed April 24, 1928, be used. In said co-pending application the jack 16 is provided with a clamping lever 18, carrying a last pin 19, an instep pad 20, and 25 a bail 21 adapted to hold the shoe against the pressure of the pad 17. The pad 17 is, in turn, provided with an inlet valve 22, which may be temporarily connected to a fluid pressure-supply 23, the amount of pressure 30 supplied to the pad 17 being controlled by means of a manually-operated valve 24, controlled preferably by means of a treadle 25. Although an operator will quickly become 35 able to judge the pressure in the pad 17 by feel alone, it is preferable that the fluid pressure supply source 23 should be equipped with a pressure gauge 26. The pad 17 is also equipped with an outlet valve 27, the primary 40 purpose of which is to release the pressure after the sole-affixing operation is completed and the cement has set, although such valve also may be operated in such cases, in which the operator should not obtain proper adjustment of the sole before the pressure becomes 45 too high to allow of movement of the upper with respect thereto.

It will thus be seen that by means of the present invention there has been provided a method of rapidly and accurately affixing soles to lasted uppers by means of adhesive cement, and since certain changes may be made in carrying out the above process without departing from the scope of the invention 50 it is intended that all matter contained in the above description shall be interpreted as illustrative and not in a limiting sense.

It is also to be understood that the following claims are intended to cover all of the 55 generic and specific features of the invention herein described, and all statements of the scope of the invention which as a matter of language might be said to fall therebetween.

Having described my invention, what I

claim as new and desire to secure by Letters Patent is:

1. A method of affixing an outer sole to a lasted upper, which includes, in combination, placing an adhesive between the adjacent surfaces of the outer sole and the lasted upper; locating the sole with respect to the upper; clamping the aforementioned parts in a pressure jack with the sole resting on a partially inflated pad; further slightly inflating the 75 pad; and, before the adhesive has set, finally adjusting said upper with respect to said soles; and thereafter inflating said pad to substantially its final pressure to affix the sole. 80

2. A method of affixing an outer sole to a lasted upper, which includes, in combination, rendering adhesive the corresponding surfaces of the sole and the upper; locating the sole with respect to the upper; clamping the aforementioned parts in a pressure jack with the sole resting on an inflatable pad; slightly inflating the pad; and, before the adhesive has set, finally adjusting said upper with respect to said sole; and thereafter inflating said pad to substantially its final pressure to affix the sole. 90

3. A method of affixing an outer sole to a lasted upper, which includes, in combination, attaching the outer sole to the lasted upper by a tack-like locating means; rendering adhesive corresponding surfaces of the sole and the upper; laying the sole by hand with respect to the upper; clamping the ensemble in a pressure jack with the sole resting on an 95 inflatable pad; slightly inflating the pad; and, before the adhesive has set, finally adjusting said upper with respect to said sole; and thereafter inflating said pad to substantially its final pressure to affix the sole. 100

4. A method of affixing an outer sole to a lasted upper, which includes, in combination, attaching the outer sole to the lasted upper by a tack-like locating means; rendering adhesive the opposed marginal surfaces of the fore part and of the entire shank of the sole and the upper; laying the sole by hand with respect to the upper; clamping the ensemble in a pressure jack with the sole resting on an 110 inflatable pad; slightly inflating the pad; and, before the adhesive has set, finally adjusting said upper with respect to said sole; and thereafter inflating said pad to substantially its final pressure to affix the sole. 115

5. A method of affixing an outer sole to a lasted upper, which includes, in combination, coating the marginal portion of the fore part of each and the shank-portion of each with an adhesive cement; after the cement has dried attaching the sole to the upper by 120 means of a tack-like locating means at the heel; applying to the cemented portions a softener for the cement to render it adhesive; laying the sole by hand with respect to the upper; clamping the ensemble in a pressure jack 130

with a sole resting on an inflatable pad; slightly inflating the pad; and, before the adhesive has set, finally adjusting said upper with respect to said sole; and thereafter inflating said pad to substantially its final pressure to affix the sole.

5 6. A method of affixing an outer sole to a lasted upper, which includes, in combination, coating the marginal portion of the fore part 10 of each and the shank-portion of each with an adhesive cement; after the cement has dried attaching the sole to the upper by means of a tack-like locating means at the heel; applying 15 to the cemented portions a softener for the cement to render it adhesive; laying the sole by hand with respect to the upper; clamping the ensemble in a pressure jack with the sole resting on an inflatable pad; slightly inflating 20 the pad; and, before the adhesive has set, finally adjusting said upper with respect to said sole; and thereafter inflating said pad to substantially its final pressure to affix the sole.

7. A method of affixing an outer sole to a lasted upper, which includes, in combination, 25 coating the marginal portion of the fore part of each and the shank-portion of each with an adhesive cement; after the cement has dried attaching the sole to the upper by means of a tack-line locating means at the heel; applying 30 to the cemented portions a softener for the cement to render it adhesive; laying the sole by hand with respect to the upper; clamping the ensemble in a pressure jack with the sole resting 35 on an inflatable pad; inflating the pad to a pressure of about 5-10 pounds per square inch; and, before the adhesive has set, finally adjusting said upper with respect to said sole; and thereafter inflating said pad to a pressure of about 40 pounds per square inch.

40 In testimony whereof I affix my signature.
WILLIAM H. BRESNAHAN.
